UNITED STATES PATENT OFFICE.

JOHN C. DAHL, OF PINE RIVER, MINNESOTA, ASSIGNOR OF ONE-HALF TO ELMER B. DAHL, OF PINE RIVER, MINNESOTA.

BROOM ATTACHMENT.

1,311,953.

Specification of Letters Patent

Patented Aug. 5, 1919.

Application filed March 10, 1917, Serial No. 153,948. Renewed February 24, 1919. Serial No. 278,932.

To all whom it may concern:

Be it known that I, JOHN C. DAHL, a citizen of the United States, residing at Pine River, in the county of Roberts and State 5 of Minnesota, have invented certain new and useful Improvements in Broom Attachment, of which the following is a specification.

My invention relates to an attachment 10 for brooms for distributing the sweeping compounds while the floor is being swept.

The primary object of my invention is to provide a device of this character in which the feeding action is controlled by a certain 15 movement of the broom.

Another object of the invention is to provide a device formed to snugly fit the broom head, so as to be easily attached thereto without danger of its becoming detached 20 by the movement of the broom in sweeping.

Another object of my invention is to provide a device of this character, which is simple and durable in construction, reliable and efficient in operation, and one which can be 25 manufactured and placed upon the market at a minimum cost.

To accomplish the above and various other objects, my invention consists essentially of a receptacle, with means for connecting it to the broom head and provided with a feeding slot, adapted to be normally covered by the broom, but so located that on a certain stroke of the broom the slot is uncovered so as to allow the material to feed 35 through.

The invention also consists in certain other features of construction and in the combination and arrangement of the several parts to be hereinafter fully described and 40 specifically pointed out in the appended claims.

In describing my invention in detail, reference will be had to the accompanying drawings, wherein like characters denote 45 like or corresponding parts throughout the several views, and in which:

Figure 1 shows the device applied to a broom.

Fig. 2 is a sectional view, showing the 50 broom in the position it occupies when a stroke is made to feed the compound.

Fig. 3 is a rear view of the device, showing the feeding opening.

In these drawings, 1 indicates the broom 55 and 2 the receptacle in which the sweeping

compound is placed. The compound is of powdered form and usually consists of a fine grain saw-dust treated with an oily preparation designed to take up the dust. This receptacle is provided with an opening 3 in its top, through which the compound is placed in the receptacle, and this opening is covered by a flap 4 hinged to the receptacle and held closed by the catch 5.

6 is the feeding opening formed in the lower part of the receptacle in the rear thereof, and this opening is controlled by a slide 7, working in guides 8 formed on each side of the feeding slot in any desirable 65 manner.

As shown in the drawings, these guides are formed by punching the material, as at 9, and turning the punched out portions over to serve as guides. The slide is regulated by a wire 10 connected to the slide and extending up through the top of the receptacle and held in any desired position by the thumb screw 11.

As will be seen from the drawings, the receptacle is shaped to conform to the shape of the broom head, that is, rounded at the top so as to fit snugly to the broom at this point and at the bottom is flared out to conform to the lower end of the broom head.

The receptacle is connected to the broom by means of the two straps 12. As will be seen from the drawings, the slot fits tightly against the broom, so that in the normal position of the broom said slot is closed and the material is prevented from passing therethrough, but when a stroke of the broom is made in a direction, with the receptacle in front, the slot is partly uncovered, due to the bending of the straw of the broom and 95 thus the material drops through.

The amount of the material fed is controlled by the position of the slide 7, though the feed is also regulated by the amount of pressure placed on the broom on the feeding 100 stroke.

It is thought from the foregoing that the advantages and novel features of my invention will be readily apparent.

I desire it to be understood that I may 105 make slight changes in the construction, and in the arrangement and combination of the several parts, provided such changes fall within the scope of the appended claims.

I claim as my invention:

1. A broom attachment, comprising a re-

110

ceptacle at one side of the broom head and having a lateral opening at its lower end normally closed by the broom fiber, the discharge of the material being controlled by the movement of the broom fiber into and out of contact with the lower end of the receptacle, due to the flexing of the broom in sweeping operation.

2. A broom attachment, comprising a receptacle at one side of the broom head having a lateral discharge opening at its lower end normally closed by the broom fiber, the

discharge of the material being controlled by the movement of the broom fiber into and out of contact with the lower end of the receptacle, due to the flexing of the broom in sweeping operation, and means for varying the size of the lateral discharge opening. 15

In testimony whereof I affix my signature in presence of two witnesses.

JOHN C. DAHL.
